UNITED STATES PATENT OFFICE.

PAUL M. HOTCHKIN, OF CHICAGO, ILLINOIS, ASSIGNOR TO CURTIS-LEGER FIXTURE CO.,
A CORPORATION OF ILLINOIS.

ATTITUDE-FIGURE FOR USE IN DISPLAYING GARMENTS AND WEARING-APPAREL.

1,318,759.

Specification of Letters Patent.

Patented Oct. 14, 1919.

Application filed December 31, 1917. Serial No. 209,675.

To all whom it may concern:

Be it known that I, PAUL M. HOTCHKIN, a citizen of the United States, residing at Chicago, in the county of Cook and State 5 of Illinois, have invented a certain new and useful Improvement in Attitude-Figures for Use in Displaying Garments and Wearing-Apparel, of which the following is a specification.

10 My invention relates to that class of devices which are constructed in the shape of a human figure upon which may be placed dresses and similar wearing apparel. These forms, as constructed at present, are 15 usually made of papier mâché with a wax head.

In the old figures these papier mâché portions, forming the arms and bust, crack and peel, due to the susceptibility of the 20 papier mâché to atmospheric conditions and changes in temperature.

My invention has for its object to provide a construction in which the bust, neck and shoulders, legs and feet are formed of 25 a composition cast in a mold taken from the natural figure, the body portion only being formed of papier mâché and the head and arms formed of wax in the usual manner.

This form of construction furnishes a 30 figure which is very much more life-like and which is not affected by atmospheric changes, and inasmuch as the bust, shoulders and upper part of the arms, which are usually shown on these figures when used to 35 display evening gowns, are formed of a composition, which is not susceptible to atmospheric changes or variations in temperature, they do not crack or peel and consequently do not deteriorate in use.

40 My means of accomplishing the foregoing objects may be more readily understood by having reference to the accompanying drawings, which are hereunto annexed and are a part of this specification, in which:

45 The figure is a view of a figure constructed in accordance with my invention, a portion of the figure being broken away to show the interior construction.

Similar reference numerals refer to similar parts throughout the entire description.

As shown in the drawings, the body portion 2, is formed of papier mâché at the lower end. It is bifurcated, and has wooden blocks 3 and 4 secured to the bifurcations, 55 there being openings 5 and 6, through the

blocks to permit the passage of rods or pipes 7 and 8. These rods extend upwardly and pass through a wooden yoke 9, and washers 10 and 11, which are secured to the wooden yoke by means of screws 13, or in 60 any other suitable or convenient manner, set screws being provided for the adjustment of the rods.

The lower ends 12 and 15 are attached to metal lasts 17 which form the lower part 65 of the foot.

The mold having been prepared for the legs, the composition 18, is poured into the mold surrounding the rods 7 and 8, and filling the spaces in the last 17. This composition is preferably formed of plaster of Paris which has mixed with it a fiber stiffening made from fragments of either hemp, rope, hair, burlap, string, etc., in sufficient quantities to give it strength. The composition 70 is then mixed with water until sufficiently plastic to be poured into the mold. A wooden block 19, is mounted in the upper part of the papier mâché body 2, and carries the supporting device 20, for holding the 75 head, bust and shoulders, on the papier mâché part of the body.

Frictional devices 22, are mounted in the arms to permit their movement. The whole 80 results in the production of an entirely 85 new form for this purpose, one which is very much more substantial and very much more life-like inasmuch as the composition forming the legs, shoulders and bust is cast in a form taken from a human figure. 90

Having described my invention what I regard as new and desire to secure by Letters Patent of the United States is:

1. A new article of manufacture, a form 95 comprising a body portion formed of papier mâché, the bust, shoulders and back portion being formed of composition, and the head being formed of wax, said composition portions being cast in a mold made from a human form.

2. A new article of manufacture, a form 100 comprising a body portion formed of papier mâché, the bust, shoulders and back and leg portions being formed of composition, and the head being formed of wax, said 105 composition portions being cast in a mold made from a human form, and means in said leg portions to maintain the figure in an upright position.

3. A new article of manufacture, a form 110

comprising a body portion formed of papier mâché, the bust, shoulders and back portion being formed of composition, said composition portions being cast in a mold made 5 from a human form.

4. A new article of manufacture, a form comprising a body portion formed of papier mâché, the bust, shoulders, back and leg

portions being formed of composition, said composition portions being cast in a mold made from a human form, and means in said leg portions to maintain the figure in an upright position. 10

In testimony whereof, I have signed the foregoing specification.

PAUL M. HOTCHKIN.
